DESIGN FOR A FLIGHT TRAINER HOOD

Richard C. Dehmel, Summit, N. J.

Application October 18, 1945, Serial No. 122,964

Term of patent 14 years

(Cl. D71—1)

To all whom it may concern:

Be it known that I, Richard C. Dehmel, a citizen of the United States of America and residing at 160 Summit Avenue, in the city of Summit, county of Union, and State of New Jersey, have invented a new, original, and ornamental Design for a Flight Trainer Hood, of which the following is a specification, reference being had to the accompanying drawings, forming a part thereof.

In the drawings:

Figs. 1 and 2 are perspective views of a flight trainer hood from front to rear showing opposite sides of my new design;

Fig. 3 is a plan view, and

Fig. 4 is a view in front elevation of the device shown in Figs. 1 and 2.

I claim:

The ornamental design for a flight trainer hood, substantially as shown.

RICHARD C. DEHTEL.
